Des. 241,369
Patented Sept. 7, 1976

241,369

DIE CUTTING APPARATUS

Henry H. Jenkins, 864 W. Hacienda Drive,
Corona, Calif. 92625

Filed July 10, 1975, Ser. No. 594,657

Term of patent 14 years

Int. Cl. D15—09

U.S. Cl. D15—128

Fig. 1

Fig. 2

Fig. 3

Fig. 4

Fig. 5

FIG. 1 is a front elevational view of the die cutting apparatus of the present invention;

FIG. 2 is a plan view of FIG. 1;

FIG. 3 is a rear view of FIG. 1;

FIG. 4 is a left end view of FIG. 1; and

FIG. 5 is a right end view of FIG. 1.

The bottom of the die cutting apparatus is plain.

I claim:

The ornamental design for a die cutting apparatus, substantially as shown and described.
